[57] CLAIM

The ornamental design for a camping trailer, as shown and described.

DESCRIPTION

FIG. 1 is a perspective view looking down and to the rear upon the upper left front of the camping trailer showing my new design, with the trailer doors in the open position;

FIG. 2 is a left side view, thereof;

FIG. 3 is a perspective left rear view, thereof;

FIG. 4 is a rear view, thereof;

FIG. 5 is a perspective right rear view, thereof;

FIG. 6 is a right side view, thereof;

FIG. 7 is a perspective right front view, thereof;

FIG. 8 is a front view, thereof;

FIG. 9 is a perspective left rear view, with dashed lines that represents a canvas enclosure, but, do not form a part of this invention;

FIG. 10 is a perspective right rear view, with dashed lines that represents a canvas enclosure, but, do not form a part of this invention;

FIG. 11 is a perspective right rear view of the trailer with the doors in the closed position; and,

FIG. 12 is a right side view of the trailer with the doors in the closed position.

The characteristic feature of my design resides in the "L" shaped roof, formed by the open doors, between the kitchen area and bed compartment.
